CLAIM

I claim the ornamental design for a bottle, substantially as shown and described.

DESCRIPTION

FIG. 1 is a top, front, right side isometric view of a first embodiment of the bottle.

FIG. 2 is a bottom, front, right side isometric view of the bottle of FIG. 1.

FIG. 3 is a front elevation view of the bottle of FIG. 1.

FIG. 4 is a rear elevation view of the bottle of FIG. 1.

FIG. 5 is a left side elevation view of the bottle of FIG. 1.

FIG. 6 is a right side elevation view of the bottle of FIG. 1.

FIG. 7 is a top plan view of the bottle of FIG. 1.

FIG. 8 is a top, front, right side isometric view of a second embodiment of the bottle.

FIG. 9 is a bottom, front, right side isometric view of the bottle of FIG. 8.

FIG. 10 is a front elevation view of the bottle of FIG. 8.

FIG. 11 is a rear elevation view of the bottle of FIG. 8.

FIG. 12 is a left side elevation view of the bottle of FIG. 8.

FIG. 13 is a right side elevation view of the bottle of FIG. 8.

FIG. 14 is a top plan view of the bottle of FIG. 8.

FIG. 15 is a top, front, right side isometric view of a third embodiment of the bottle.

FIG. 16 is a bottom, front, right side isometric view of the bottle of FIG. 15.

FIG. 17 is a front elevation view of the bottle of FIG. 15.

FIG. 18 is a rear elevation view of the bottle of FIG. 15.

FIG. 19 is a left side elevation view of the bottle of FIG. 15.

FIG. 20 is a right side elevation view of the bottle of FIG. 15.

FIG. 21 is a top plan view of the bottle of FIG. 15.

FIG. 22 is a top, front, right side isometric view of a fourth embodiment of the bottle.

FIG. 23 is a bottom, front, right side isometric view of the bottle of FIG. 22.

FIG. 24 is a front elevation view of the bottle of FIG. 22.

FIG. 25 is a rear elevation view of the bottle of FIG. 22.

FIG. 26 is a left side elevation view of the bottle of FIG. 22.

FIG. 27 is a right side elevation view of the bottle of FIG. 22; and,

FIG. 28 is a top plan view of the bottle of FIG. 22.

The broken lines in the drawings illustrate portions of the bottle that form no part of the claimed design.
